UNITED STATES PATENT OFFICE.

LEONHARDT SESSLER, OF BOTTERNWEILER, NEAR ZUMHAUS, GERMANY.

CULTIVATOR.

1,046,872.

Specification of Letters Patent. Patented Dec. 10, 1912.

Application filed July 8, 1912. Serial No. 708,270.

To all whom it may concern:

Be it known that I, LEONHARDT SESSLER, a subject of the Emperor of Germany, and residing at Bottenweiler, near Zumhaus, in 5 Bavaria, Germany, have invented certain new and useful Improvements in Cultivators, of which the following is a specification.

It is rather laborious and toilsome to work 10 the furrowed soil if interspersed with loose, undecomposed stable dung, with the cultivators known up to now. In order to overcome the difficulties arising from this cause, I propose to substitute rotary cutting-disks 15 or cutters for the resilient teeth at present in use, the object of these cutters being to cut up the said dung so as to allow of a proper working of the soil from the beginning. Some of the elastic teeth may, however, be retained if desired, and at any rate 20 I prefer to make the said cutters adjustable, as is more fully described hereinafter.

The accompanying drawing shows, as an example, one form of construction of my 25 improved cultivator, there being in this instance all the resilient teeth replaced by the rotary cutters in question.

Figure 1 is a side view of the machine, and Fig. 2 is a plan of the same.

30 The axles *b* which may be turned simultaneously and uniformly by means of a hand lever, as shown, are provided with resilient bars *c* secured to said axles by U-shaped double bows *d*. These bows may be shifted 35 horizontally along the axles and the bars may be shifted vertically in the said bows so as thereby to adjust the tools carried by the bars horizontally as well as vertically, according to the nature of the soil to be 40 treated.

The tools in question consist of the rotary cutting-disks *g* which may be individually adjusted at the bars *c* by U-shaped double bows *e* resembling closely the bows *d*. The 45 cutters *g* are held by axles *f*, preferably

curved, and the bows *e* serve for attaching the said axles to the bars *c*. The axles *f* may, therefore, be bodily adjusted toward or from the bars *c*, and where curved axles are employed, the adjustment can be effected also in regard to the angular position of the said rotary cutters. Furthermore, the cutters may be arranged either at the left hand side or the right hand side of the bars *c* (see Fig. 2) and thus the possibility is offered to symmetrically force the earth either in a direction to or away from the sloping sides of the furrow.

What I claim as new and desire to secure by Letters Patent is:

1. In a cultivator, the combination with a frame, of a rotary cutter, a bar adapted to be adjusted horizontally and vertically, a curved axle for carrying said cutter, and a clamp for adjustably securing said axle to 60 said bar but permitting adjustment of said cutter toward or from said bar, substantially as and for the purpose set forth.

2. In a cultivator, the combination with the frame, of a rotary cutter, a bar carried 70 by said frame, a curved axle for carrying said cutter, and a U-shaped double bow clamping said axle against said bar, for the purpose as described.

3. In a cultivator the combination with 75 the frame, of straight axles adapted to be turned, elastic bars held by said axles, U-shaped double bows connecting the axles with the bars, curved axles held by the latter, other U-shaped bows connecting these 80 axles with the said bars and rotary cutting-disks supported by said curved axles, for the purpose as described.

In testimony whereof I affix my signature in presence of two witnesses.

LEONHARDT SESSLER.
